LIQUID FUEL COMBUSTION APPARATUS, FOR JET-PROPULSION ENGINES, GAS TURBINES, OR OTHER PRIME MOVERS

Squire R. Jackson, Burnley, and George S. Cooper, Rawtenstall, England, assignors to Joseph Lucas (Industries) Limited, Birmingham, England

Filed Feb. 20, 1964, Ser. No. 346,278

1 Claim. (Cl. 60—39.74)

This invention relates to an improved liquid fuel combustion apparatus, for jet-propulsion engines, gas turbines, or other prime movers and of the kind comprising a combustion chamber of substantially circular cross-section, a liquid fuel burner at the inlet end of the combustion chamber, a swirler surrounding the burner, an air jacket surrounding the combustion chamber and having an air inlet at one end, and a nose piece extending from the combustion chamber towards said inlet.

According to the invention in a liquid fuel combustion apparatus of the kind specified the nose piece is connected to the combustion chamber through the intermediary of a hollow tapering part of generally circular cross-section the nose piece being shaped to define between it and said part a pair of substantially segmental openings through which air can flow to the swirler.

An example of the invention will now be described with particular reference to the accompanying drawings in which:

FIGURE 1 is a sectional side view of a part of an apparatus in accordance with one embodiment of the invention,

FIGURE 2 is a part sectional end view of a pair of adjacent combustion chambers of the apparatus shown in FIGURE 1, and

FIGURE 3 is a cross-sectional view on the line 3—3 in FIGURE 1.

Referring to the drawings there is provided a plurality of annularly arranged combustion chambers 3 of circular cross-section which are located within an annular air jacket 4. The combustion chambers are interconnected by pressure balancing pipes 5 and are spaced from the walls of the air jacket 4 which converge at one end to define an annular air inlet 6.

Centrally disposed within the inlet end of each combustion chamber is a liquid fuel burner 7 which is surrounded by a swirler 8 located in a substantially conical end plate 9 of the combustion chamber. Moreover, secured to the inlet end of the combustion chamber is a hollow tapering part 10 of generally circular cross-section throughout its length, whilst to the narrower end of said part 10 is connected a nose piece 11. In longitudinal sectional side elevation (as shown in FIGURE 1) the combined part and nose piece is of a symmetrical form with its surface presented to the outer annular wall of the air jacket 4, curving progressively inwards (in an upstream direction) towards the centre of the annular row of combustion chambers, more sharply than the surface, presented to the inner annular wall of the air jacket, which curves progressively outwards. From FIGURES 2 and 3, it will be seen that the combined nose piece 11 and part 10 is symmetrical in a plane at right angles to the plane of the longitudinal cross-section of FIGURE 1. However, the maximum width of the nose piece 11 in this plane is less than the narrower end of the part 10 so as to define, at opposite sides of the nose piece 11 a pair of substantially segmental openings 12 through which air can enter the part 10 and flow to the swirler. Moreover

2

as viewed in this direction the sides of the nose piece adjacent the part 10 are parallel and only its outer end tapers.

Ribs 18 span the openings 12 between the side wall of the nose piece 11 and the edge of the part 10. Inside the nose piece are a pair of brackets 19, which are joined together, as shown in FIGURE 3, in the plane of the section of FIGURE 1. The edges of the nose piece 11 have stiffening strips 21.

10 In the outer surface of the nose piece 11, presented to the outer annular wall of the air jacket is formed an aperture 13 for accommodating a fuel supply pipe 14 for the burner 7, this pipe also extending through the outer wall of the air jacket. Moreover, the width of the nose piece 11 as viewed in FIGURE 3 is approximately equal to the diameter of the swirler 8 so as to protect the latter from the direct impingement of air entering the part 10.

A proportion of the air entering the part 10 flows through the swirler 8 to the combustion chamber. Another part of this air flows over the conical end plate 9 of the combustion chamber and enters the combustion chamber through flared openings therein, and around the outer edge thereof.

25 The combined combustion chamber 3, part 10 and nose piece 11 is supported in spaced relationship within the air jacket 4 by means of a forked bracket 15 secured to the jacket and embracing a reduced portion 10a of the part 10 adjacent the nose piece 11. The reduced portion of the nose piece is formed as a result of the formation of a pair of recesses 16 in the outer surface of the part 10, and a pin 17 passes transversely through the portion 10a and the two limbs of the bracket 15.

30 Having thus described our invention what we claim as new and desire to secure by Letters Patent is:

35 35 Liquid fuel combustion apparatus for gas turbine engines comprising a combustion chamber of substantially circular cross-section having an inlet at an upstream end thereof and an outlet at a downstream end thereof, a liquid fuel burner at the upstream end of the combustion chamber, a swirler surrounding the burner, an air jacket surrounding the combustion chamber having an air inlet at an upstream end of the air jacket adjacent to the upstream end of the combustion chamber, a hollow tapering part of generally circular cross-section connected to the combustion chamber near its upstream end, a nose piece connected to the hollow tapering part, the nose piece being of non-circular cross-section to define between it and the hollow tapering part, a pair of substantially segmental openings, the position of the nose piece being arranged to prevent direct impingement of air entering the openings upon the swirler, said openings being disposed on opposite sides of a plane passing through a longitudinal axis of the combustion chamber and swirler, and the edges of the openings nearest to said plane being spaced apart by a distance at least equal to the width of the swirler.
